UNITED STATES PATENT OFFICE.

RICHARD D. CHANDLER, OF HYDEPARK, MASSACHUSETTS.

DESIGN FOR A LAMP-SHADE.

SPECIFICATION forming part of Design No. 36,185, dated December 30, 1902.

Application filed May 19, 1902. Serial No. 108,109. Term of patent 3½ years.

To all whom it may concern:

Be it known that I, RICHARD D. CHANDLER, a citizen of the United States, residing at Hydepark, in the county of Norfolk and State 5 of Massachusetts, have invented and produced a new, original, and ornamental Design for Shades for Lamps, of which the following is a specification, reference being had to the accompanying drawings, forming part thereof. 10 Figure 1 is a side elevation of a shade for lamps, showing my new design. Fig. 2 is a plan view.

As shown in the drawings, the leading or 15 material feature of my design consists of beads A A, with cut surfaces and rosettes B B, arranged as shown in Fig. 1. The lines of beads are so arranged as to form squares with

diagonals and having rosettes at all the intersections of lines. The top of the shade is surrounded by beads and rosettes alternating 20 and set upright.

Having described my invention, what I claim as new, and desire to secure by Letters Patent, is—

The ornamental design for a lamp-shade, 25 as herein shown and described.

In testimony whereof I have signed my name to this specification in the presence of two subscribing witnesses.

RICHARD D. CHANDLER.

Witnesses:

M. E. COVENEY,
A. L. HODGDON.
